M. ALLAND

MULTICOLOR FOUNTAIN PEN

Filed Oct. 3, 1925

UNITED STATES PATENT OFFICE.

MAURICE ALLAND, OF ATLANTIC CITY, NEW JERSEY.

MULTICOLOR FOUNTAIN PEN.

Application filed October 3, 1925. Serial No. 60,223.

The object of the invention is to provide improvements in fountain pens, and particularly in that type which permits, by simple adjustment, writing in two or more colors.

Another object has been to provide a construction which facilitates the flow of air into the reservoir to replace the ink or other liquid as the latter flows therefrom by way of a feed-member and the usual pen-point.

A further object is to provide means, whereby when use of the pen is discontinued, a relatively simple manipulation serves to shut off the flow of liquid before it reaches the pen-point, so that no ink can escape from the pen regardless of the position in which it is carried, or from the pen and feed member into the reservoir.

Still another object is to provide, in combination with the foregoing features, means for filling the reservoir of the instrument with water or the like, in a manner which insures a maximum quantity of such liquid so as to serve for the pen as long as possible.

And a still further object is to provide indicating means upon the outside of the pen, whereby the user can tell at any time whether the liquid supply is free to flow, or the shut-off valve mechanism has been operated, besides combining all of these improved features with means for supporting a plurality of soluble ink-pellets, one operatively positioned adjacent to the pen-point and the remainder held in reserve, spaced away from said pen-point and free from the liquid which passes from the reservoir through or by the feed-member to the said pen-point.

With these and other objects and advantages of the invention, together with details of the construction and operation of the same, the invention in one form is herein-after described in conjunction with the accompanying drawings in which Fig. 1 is a side elevational view of a writing instrument comprising a fountain pen having a part of one end broken away and the end wall of the reservoir removed; Fig. 2 is a similar view of the instrument, also having portions of the side walls broken away, and with a cap (Fig. 3) shown in alignment therewith; Fig. 4 is an elongated view of the several parts of the pen in disassembled relation; Fig. 5 is a bottom plan view of the lower portion of the instrument; Fig. 6

comprises both an end and a side elevation of the closure member for the lower end of the reservoir; Fig. 7 is a group of three central longitudinal sections, showing the feed-member, feed-member holder and the closure member of Fig. 6 in alignment as normally assembled; Fig. 8 is a side elevation of the normal upper side of the feed-member holder, shown in the center of Fig. 7, and Fig. 9 is a section on the line 9—9 of Fig. 5.

Referring to the drawings, a reservoir 1 is provided with a piston or plunger 2, through which a shaft 3 is adapted to slide freely and with which said shaft is adapted to be temporarily secured for reciprocation of the plunger by means of external manual operation of the shaft. The adjacent or upper end of the reservoir is normally closed by a member 4, through which the shaft slides, but which in Fig. 1 is shown in open position for removing the plunger or the like, said closure being shown in its closed position in Fig. 2. The upper freely projecting end portion of the instrument forms a handle for operating the shaft and plunger when required, but also preferably embodies a magazine pencil.

The lower portion of the reservoir is closed by a member shown both in Fig. 6 and at the top of Fig. 7. This closure member comprises a tube 5 closed at its upper end 6, which latter is externally threaded at 7 for securing the member within the otherwise open lower end of the reservoir. The central portion of this tube is enlarged at 8, and its surface forms a continuation of the corresponding surface of the reservoir 1, while a sector 9 of the threads 7 is cut away to provide for the passage of air into the reservoir from an angularly shaped capillary bore 10, which enters the outer surface of the enlarged portion 8, immediately adjacent to the upper limit of the latter, and leaves said closure member through the upper surface of said enlarged portion.

The feed member 11, which supports the pen-point 12, is provided with a longitudinal slot 13 upon that portion of its surface over which the pen-point normally lies. At the upper end the slot 13 enters a transversely extending saw-cut 14, and this resulting bifurcated end portion is normally secured within a tubular member 15 constituting a feed member holder (shown in Figs. 7 and 8), having a closed upper end 16, and ex-

tending slidably into the tube 5 of the reservoir closure. The lower portion of the member 15 is radially enlarged at 17 and provided with a reversely turned cylindrical flange 18, which when assembled overhangs the lower reduced end portion 19 of the member 5. It will also be noticed that the upper end portion 6 of the member 5 is provided with a radially extending segmental slot 20 in which normally extends a pin 21, surrounded by water-tight cement 21' and protruding from the upper end portion of the member 15, to limit the relative angular movement of the members 5 and 15 with respect to each other. The latter of said last-named members is also provided with a capillary bore 22, which when the members 5 and 15 are in one angular position permits water within the reservoir to flow therefrom and into the interior of the said last-named of these two oscillatable members, whence it flows into the saw-cut 14 and through the groove 13 of the feed-member 11 to the pen-point 12, where, while still beneath said point, it passes over a soluble ink-pellet in the cup 23 of the multi-holder 24 within the aperture 25, the pellet being gradually dissolved and thereby causing ink to flow to and from the pen-point upon the writing material in use.

In the operation of this improved writing instrument, it is assumed that the reservoir has previously been filled with clear water. The upper end portion of the instrument is in its normal lower position as shown in Fig. 2. The members 15 and 5 are in such position that, when viewing them as positioned in Fig. 5, the aperture 22 is closed. An ink-pellet of a given color such as red is in position in the aperture 25 and, if desired, a similar pellet but of a different color such as black, is in the other cup of the holder, and positioned within the upwardly closed aperture or recess 26. The member 15 is then manually oscillated in the direction of the "O" in Fig. 8 and until it can turn no farther. At this point the bore 22 is in the position shown in Fig. 5 and will permit water from within the reservoir to flow therefrom into the interior of the member 15, directly into the saw-cut 14, feed-member slot 13, over the ink-pellet as above described, and from the pen-point, the air pressure within the said reservoir being maintained with unfluctuating regularity by the direct flow of air inwardly through the bore 10 from the exterior of the instrument. Finally, if it is desired to discontinue writing, the members 15 and 5 are simply turned as far as possible in the direction of the "C" in Fig. 8 and no more water can flow to the pen from the reservoir. However, if instead of red ink, it is desired to write with ink of a black color, or in fact any color that may be represented by the reserve pellet in the recess 26,

the holder 24 is simply removed manually from the operative position shown in Fig. 7 and reversed end for end, so that the remainder of the red pellet is now held in reserve and the black pellet is operatively positioned within the aperture 25, when, as the clear water from the reservoir flows over it, ink of the same color is made and flows as hereinbefore described from the pen-point. It is to be understood of course that pellets of any desired colors can be used, and the invention is also not necessarily limited to a holder or other provisions for but two colors, the device described merely representing the broad principle involved, namely, the provision of a plurality of soluble ink-pellets of different colors (or like colors for that latter) for use as and when wanted.

Having thus described my invention, what I claim and desire to protect by Letters Patent of the United States is:

1. A fountain pen comprising a reservoir, a closure therefor, a feed member holder telescoped in and rotatable relatively to said closure, a feed member in said holder, a point jointly positioned by said holder and feed member, said feed member having a channel leading to said point and a transverse cut communicating with the channel, said holder having an opening therethrough in constant communication with said cut, said closure having an opening therethrough communicating with the interior of the reservoir, the rotation of the feed member holder controlling the registration and non-registration of said openings.

2. A fountain pen comprising a reservoir, a closure therefor, a feed member holder telescoped in and rotatable relatively to said closure, said holder at its lower portion having an exterior flange overlapping the lower end of the closure, a feed member in said holder, a point jointly positioned by said holder and feed member, said feed member having a channel leading to said point and a transverse cut communicating with the channel, said holder having an opening therethrough in constant communication with said cut, said closure having an opening therethrough communicating with the interior of the reservoir, the rotation of the feed member holder controlling the registration and non-registration of said openings.

3. A fountain pen comprising a reservoir, a closure therefor, a feed member holder telescoped in and rotatable relatively to said closure, said holder at its lower portion having an exterior flange overlapping the lower end of the closure, a feed member in said holder, a point jointly positioned by said holder and feed member, said feed member having a channel leading to said point and a transverse cut communicating with the channel, said holder having an opening

therethrough in constant communication with said cut, said closure having a portion extending into the reservoir provided with an opening therethrough communicating with the interior of the reservoir and having a sector cut away on its periphery in line with the last mentioned opening, the rota-

tion of the feed member holder controlling the registration and non-registration of said openings.

In testimony whereof I have affixed my signature.

MAURICE ALLAND.
